VENETIAN BLIND CONTROL MECHANISM

Martin L. Wiener and Walter F. Nelsen, San Leandro, Calif., assignors to Ry-Lock Company Ltd., San Leandro, Calif., a corporation

Application April 27, 1935, Serial No. 18,552

9 Claims. (Cl. 156—17)

This invention relates to control mechanisms for Venetian blinds and is directed particularly to a control mechanism for tilting the slats of the blind to different angular positions transversely.

The principal objects of this invention are to provide a Venetian blind tilting mechanism which will operate with great ease; one in which the control mechanism is concealed so that the structure is neat in appearance, and one which is compact in construction in order that the horizontal tilt rail of the blind structure will be supported relatively close to the head rail, thereby eliminating to a marked degree the undesirable light space between these two parallel rail members when the blind is closed.

A further object of this invention is to provide a device wherein the reaches of the blind tilting cord may be maintained in trained relation about a substantial and constant portion of the peripheral groove of the control sheave regardless of the direction of movement of the cord. It is also our purpose to provide guide elements for the tilting cord of such form that the cord may be pulled from any angle relative to the control mechanism without any tendency to binding.

A further object of the invention is to produce a simple and inexpensive device and yet one which will be exceedingly effective for the purpose for which it is designed.

These objects we accomplish by means of such structure and relative arrangement of parts as will fully appear by a perusal of the following specification and claims.

In the drawing similar characters of reference indicate corresponding parts in the several views:

Figure 1 is a sectional elevation of the blind tilting mechanism illustrating the same as mounted on the head rail of the Venetian blind.

Figure 2 is a front elevation illustrating the operating mechanism in dotted lines.

Figure 3 is a top plan of the mechanism with the upper portion of the frame removed.

Figure 4 is a bottom plan view of the blind tilting mechanism.

Fig. 4a is a side view of the supporting bracket, detached.

Referring now more particularly to the characters of reference on the drawing, the blind tilting and supporting device comprises a face or frame plate 1 formed along the top edge with a right angle flange 2 and along the lower portion of one side edge with a right angle end plate 3. Formed intermediate the ends of the frame plate

1 and extending in the same direction as and parallel to the flange 2 and transversely of the end plate 3 is a base plate 4. The head rail H fits closely at one end between the flange 2 and plate 4, and is rigidly secured thereto by suitable means, the rail resting on the plate 4.

A segmental spur gear 5 is rigidly secured to the end of the tilt rail B by suitable means such as screws 6 projecting through the gear into the rail. A supporting angle-flange 7 formed on the lower edge of the gear and extending at right angles thereto under the rail provides an additional support for the rail B relative to the gear 5.

Extending axially from gear 5 is a rigid stub shaft 8 which is circumferentially grooved adjacent its outer end, as at 9, in order that this end of the shaft may be rotatably and removably mounted but axially immovable in a vertical key hole slot 10 formed in the end plate 3.

The other end of the tilt rail B is supported by means of an end pin and bracket having a bayonet slot (not shown). The horizontal blind slats S are suspended as usual from the tilt rail by spaced ladder tapes T.

Rotatably journaled in and projecting through the base plate 4 is a vertical shaft 12 whose axis is closer to plate 1 than the axis of the horizontal longitudinal shaft 8. Secured to the lower end of the vertical shaft 12 is a special form of worm gear G comprising a disc or head 13 having spirally disposed and overlapping segmental ridges 14 depending from the lower face of the head, as illustrated in Figure 4, and forming teeth for meshing engagement with the teeth of the segmental spur gear 5; the worm being disposed so that adjacent its rim it is tangent to the gear.

Mounted on the upper end of the shaft 12 above the base plate 4 is a sheave 15 about which are trained the reaches of the tilting cord C. The tilt cord C after passing about the sheave 15 extends out through outwardly flaring guide thimbles 16 formed in the outer face of the frame plate 1. The lines then depend down in front of the blind slats to a termination in pull knobs (not shown).

Positioned between the sheave 15 and the outwardly flaring guide thimbles 16 is a guide bar 17 formed with spaced holes through which the lines of the cord pass. These holes are spaced apart less distance than the diameter of the sheave whereby the guide bar 17 will hold the cord in positive engagement with the sheave for a considerable portion of its circumference at all times regardless of the direction the cord is moving.

- This structure is illustrated in Figure 3. In use, the end of the guide bar through which the cord is running on the sheave will be drawn against the sheave as illustrated, thus causing the cord 5 to be drawn down into the sheave groove and provide greater peripheral engagement therewith than would otherwise be the case.
- In use, the blind tilting mechanism is mounted on one end of the head rail as illustrated in Figure 1. The head rail extends between the flange 2 and base plate 4 and is cut out to encase the sheave 15 and adjacent parts. Suitable screws hold the head rail in rigid connection with this tilting mechanism and the mechanism is secured 10 to the window casing by other screws which extend through the flange 3 and hold the same against the casing. The frame of the tilting mechanism thus serves also as a supporting bracket for the head rail.
- When it is desired to tilt the head rail, the cords, depending down in front of the slats, are moved in opposite directions relative to each other causing the sheave 15 and flat worm gear G to rotate. As the flat worm gear rotates, the peculiarly shaped spiral teeth thereof successively 15 engage the teeth of the segmental spur gear and rotate the same causing the cooperating tilt rail to tilt resulting in all the slats tilting as illustrated in dotted lines in Figure 1.
- Due to the use of outwardly flaring guide thimbles 16 for the tilt cords, they may be operated from any angle with equal ease. The frame plate 1, in which the thimbles are formed, also forms a shield for the gears and sheave concealing the 20 same and thereby making the device very neat in appearance.

The tilt rail with the segmental spur gear secured thereto, as well as the blind itself, may be entirely removed from the supporting and tilting 40 device by first detaching the end pin (on one end of the tilt rail) from the bayonet slot in the bracket (not shown) and then removing the circumferentially grooved shaft (on the other end of the tilt rail) from the key hole slot in the end 45 plate 3.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the 55 appended claims.

Having thus described our invention, what we claim as new and useful and desire to secure by Letters Patent is:

1. In a Venetian blind, a tilt rail, a spur gear 60 fixed to said rail at one end thereof, means pivotally supporting said gear, a worm mounted above the gear on a vertical axis and comprising a flat horizontal disc and depending spiral overlapping ridges thereon forming gear engaging teeth, and means to rotate said worm.

2. In a Venetian blind a tilt rail, a spur gear fixed with said rail at one end, means pivotally supporting said gear, a worm mounted above the gear on a vertical axis and comprising a flat hori-

zontal disc and depending spiral overlapping ridges thereon forming gear engaging teeth, a sheave fixed axially with and above the worm disc, and a pull cord passing about the sheave.

3. In a Venetian blind having a head rail, a 5 tilt rail thereunder, and a tilt controlling mechanism therefor, a supporting frame in which said mechanism is mounted adapted to be secured on a window casing, means on said frame to support one end of the head rail, and means between the 10 tilt controlling mechanism and the tilt rail to support the latter.

4. In a Venetian blind having a head rail and a tilt rail thereunder, a tilt controlling mechanism comprising a supporting frame which includes a horizontal base plate secured to and on which the head rail rests, and a front plate depending from the base plate, a spur gear mounted on a horizontal axis under said base plate and supporting the adjacent end of the tilt rail, a 20 worm mounted with a vertical axis on and under the plate and comprising a flat disc, and depending spiral ridges forming gear engaging teeth, a sheave fixed axially with the worm above the base plate, the head rail being recessed to clear 25 the sheave, and a control cord about the sheave, the front plate having guide openings through which the reaches of the cord project.

5. In a tilt controlling mechanism for a Venetian blind, a sheave, a control cord passing about 30 the sheave and having pull reaches leading from opposite sides thereof, fixed guide thimbles through which the reaches pass spaced from the adjacent periphery of the sheave, and a plate disposed between the thimbles and the sheave and 35 having openings through which the reaches of the cord pass, the spacing of said openings being less than the diameter of the sheave.

6. In a Venetian blind, a tilt rail, a segmental spur gear secured to said rail at one end, means 40 pivotally supporting said gear, a worm mounted adjacent the gear and in cooperation therewith, the endmost teeth of the gear being wider than the space between the worm ridges whereby to form stops to limit the rotation of the worm and 45 gear.

7. In a Venetian blind having a head rail and tilt rail thereunder, the combination of a supporting frame adapted to be secured to a window casing, means on said frame to support one end 50 of the head rail, and means on said frame to pivotally support one end of the tilt rail.

8. In a Venetian blind having a head rail, a tilt rail thereunder, and a tilt controlling mechanism therefor, a supporting frame in which said mechanism is mounted adapted to be secured on a window casing, means on said frame to support one end of the head rail, a spur gear included with the tilt controlling mechanism secured to one end of the tilt rail, and a stub shaft projecting axially of the gear from said end of the tilt rail and rotatably supported on the frame.

9. A device as in claim 8 in which the stub shaft is formed with a circumferential groove adjacent its outer end, the frame having a vertical key hole slot formed therethrough and in which the grooved shaft engages.
